UNITED STATES PATENT OFFICE.

OTTO HEINEMAN, OF NEW YORK, N. Y., ASSIGNOR TO GENERAL PHONOGRAPH CORPORATION, A CORPORATION OF NEW YORK.

DESIGN FOR A RADIO LOUD SPEAKER.

Application filed February 20, 1925. Serial No. 12,439. Term of patent 7 years.

To all whom it may concern:

Be it known that I, OTTO HEINEMAN, a citizen of the United States of America, residing in the borough of Manhattan, city, county, and State of New York, have invented a new, original, and ornamental Design for Radio Loud Speaker, of which the following is a specification, reference being had to the accompanying drawing, forming a part thereof.

This figure is a perspective view of a

radio loud speaker illustrating my new design.

I claim:

The ornamental design for a radio loud speaker substantially as shown.

This specification signed and witnessed this 5th day of December, 1924.

OTTO HEINEMAN.

Witnesses:

ROSE BLOCH,

JOHN L. LOTSCH.
